UNITED STATES PATENT OFFICE.

PHILIP D'HUC DRESSLER, OF CLEVELAND, OHIO, ASSIGNOR TO AMERICAN DRESSLER TUNNEL KILNS, INC., OF CLEVELAND, OHIO, A CORPORATION OF NEW YORK.

RECIPROCATING CAR KILN.

Application filed September 14, 1925. Serial No. 56,117.

The general object of my present invention is to provide an improved kiln especially adapted for such heat treating operations as forming the enamel coating on enamelled ware. More specifically, the object of my invention is to provide an improved kiln well adapted for use in heat treating operations of the kind referred to and characterized by the simple and effective provisions made for uniformly heating the wares treated.

The various features of novelty which characterize my invention are pointed out with particularity in the claims annexed to and forming a part of this specification. For a better understanding of the invention, however, its advantages and specific objects attained with its use, reference should be had to the accompanying drawings and descriptive matter in which I have illustrated and described preferred embodiments of the invention.

Of the drawings:

Fig. 1 is a plan view;
 25 Fig. 2 is a sectional elevation on the line 2—2 of Fig. 1;
 Fig. 3 is a transverse section on the broken line 3—3 of Fig. 2;
 30 Fig. 4 is a partial section on the line 4—4 of Fig. 1; and
 Fig. 5 is a partial sectional elevation taken similarly to Fig. 2, illustrating a modified construction.

In the drawings and referring first to the construction shown in Figs. 1, 2, 3 and 4, A represents the kiln chamber which has one closed end A' and is provided at its other end with a door B removable to permit access to the interior of the kiln, and to permit the insertion and removal of the kiln car C when this is necessary. Normally, however, the door B is closed and the car C, which has wheels C' running on track rails a, is moved back and forth between two end positions, in one of which the right hand end of the car, as seen in Fig. 2, is immediately adjacent the door B, and in the other of which the left hand end of the car is immediately adjacent the closed end of the kiln. The car has a refractory top portion, a central portion of which is recessed to provide a ware receiving platform advantageously formed by a slab or slabs C² of highly refractory material as carborundum.

55 As shown in the drawings, the articles to

be enamelled or otherwise heated, are mounted on trays I which rest on the work supporting platform C² of the car, and the articles are heated wholly or mainly by radiation from the heated roof of the kiln. A large portion of the heat absorbed by the articles with the special construction illustrated in Figs. 1 to 4, is radiated from carborundum slabs F forming the central portion of the roof or ceiling of the kiln chamber directly above the kiln car, when the latter is in the central or intermediate position shown in Fig. 2. The wares treated also absorb heat by radiation from the slabs f or fa which form the sections of the kiln roof or ceiling above the wares, when the car is in either end position. The carborundum slabs F form the bottom wall of a combustion chamber E into which burning gases pass through distributing ports h' from chambers or flues h at the opposite sides of the chamber E. As shown, each passage h, has an outwardly inclined portion at each end to which combustion air and fluid fuel are supplied, H representing fuel supply pipes. From the combustion chamber proper, the heating gases pass through ports A⁴ in the two spaced apart barrier walls A⁵ forming the ends of the combustion chamber E into the heating chambers e and ea. The latter extend from the barrier walls A⁵ to barrier walls A⁶ at the ends of the active portion of the kiln chamber. The bottom walls of the chambers e and ea are formed by the bricks or slabs f and fa which may be of carborundum. G and GA represent stack outlets from the heating chamber e and ea respectively, and I represents pipe outlets from the high temperature portion of the kiln chamber proper for the escape of gases or vapors evolved in the enamelling or other treatment to which the articles are subjected in the kiln.

The means employed for giving the car C its reciprocating movements may be of any suitable character. The means shown for this purpose comprise a cable D attached at its ends to the ends of the car and running around pulleys D' and D² at the opposite end of the kiln, power being applied to one of these pulleys by any suitable mechanism (not shown). The end portions of the cable D pass through slots formed for the purpose in the kiln end wall A' and kiln door B, and

the portion of the cable passing between the pulleys D' and D^2 , runs through a channel A^{10} formed in the foundation of the kiln structure. The kiln is formed with doorways A^2 which serve as ware ingress and egress ports. As shown, the doorways A^2 are normally closed by doors A^3 , and are located at the opposite sides of the positions occupied by the work supporting platform C^2 of the car when the latter is in its end positions.

Provisions are made for minimizing the circulation of the kiln atmosphere and thereby avoiding injurious effects of such circulation on the ware, and provisions are also made for protecting the track rails and metallic under portions of the car, and the means for moving the latter back and forth through the kiln, against exposure to undesirably high temperatures. The provisions made for this purpose comprise car end portions C^3 which may be in the form of asbestos aprons extending from the refractory body of the car to the floor level of the kiln, and notched for the passage of the track rails a , sand sealing troughs K' , and depending aprons or flanges C^4 , carried by the sides of the car and extending into said troughs, and the usual rib and groove formations at the sides of the car and the adjacent side walls of the kiln chamber, and the transverse barrier walls or depending baffles A^5 and A^6 which extend down from the roof of the kiln chamber into close proximity with the top of the car C .

When the car C is in either end position, one or both of the adjacent doors A^3 are removed and the treated material then on the car platform is removed and fresh ware to be treated in the kiln is put in its place, after which the doors A^3 are closed. The car is then moved into the central position shown in Fig. 2, and thence into the position in which the kiln car platform C^2 is adjacent the other doorways A^2 . In some cases the movement of the car between its two end positions may be continuous or practically so, but in enamelling ware and for some other uses, the movement of the car is ordinarily intermittent, and the car is held stationary with its work receiving platform beneath the central highly heated portion of the kiln roof while the ware receives the major portion of the heat absorbed by it.

The general features of the invention are obviously not dependent on the character of the kiln heating means employed. For example, in lieu of the fuel burning provisions of Figs. 1, 2, 3, and 4, I may advantageously provide electrical kiln heating means, and in Fig. 5, K , h , and ha represent electrical resistance heater elements which line the inner surface of the kiln roof sections corresponding to the sections F , f , and fa of Fig. 2, and which may be of the type shown in

Patent No. 925,902 to J. L. Harper and W. J. Larkworthy, granted June 22, 1909.

A kiln constructed and operating as described possesses various desirable characteristics. In particular, it is comparatively easy to operate both with respect to the loading and unloading of the wares treated, and with respect to the control of the kiln temperature conditions. The invention is especially characterized by the uniform manner in which articles located on different portions of the platform C are heated. It is true that the heat absorbed from the end roof plates f , for example, by a piece of ware loaded on the car when the latter is beneath the plates f , must depend somewhat on the position of the piece of ware on the platform C^2 . If the piece is near the end of the platform adjacent the central portion of the kiln, it will be beneath the plates f for a shorter time, and hence will absorb less heat from the latter than will a piece of ware located on the platform C^2 at a greater distance from the center of the kiln. This is substantially compensated for, however, when the platform C^2 is moved into its other end position, for, generally speaking, the aggregate time beneath the plates f and fa of any one article treated will be the same regardless of what portion of the platform C^2 the article rests upon.

While in accordance with the provisions of the statutes, I have illustrated and described the best form of embodiment of my invention now known to me, it will be apparent to those skilled in the art that changes may be made in the form of the apparatus disclosed without departing from the spirit of my invention as set forth in the appended claims, and that in some cases certain features of my invention may be used to advantage without a corresponding use of other features.

Having now described my invention what I claim as new and desire to secure by Letters Patent, is:

1. In a kiln the combination with a kiln chamber having two spaced apart ports for the inlet and egress of ware, of a ware support movable back and forth in said kiln chamber to permit wares loaded on said support through either port to be removed through the other port.
2. In a kiln the combination with a kiln chamber having two spaced apart ware inlet and egress ports, of a reciprocating carrier in said chamber and having a ware supporting platform and movable back and forth between one end position in which said platform is adjacent one of said ports, and a second end position in which said platform is adjacent the second port, whereby ware loaded on the platform when adjacent one of said ports may be removed from said platform when opposite the other of said ports.

3. In a kiln the combination with a kiln chamber having two spaced apart ware inlet and egress ports, of a reciprocating carrier in said chamber and having a ware supporting platform and movable back and forth between one end position in which said platform is adjacent one of said ports, and a second end position in which said platform is adjacent the second port, and means for 10 supplying heat to the wares on said platform at a relatively rapid rate while said platform is in a position intermediate said end positions and for supplying heat to said wares at a slower rate when said platform is in 15 either end position.
4. In a kiln the combination with a kiln chamber formed with two spaced apart ware inlet and egress ports and a carrier having a ware support platform movable in said 20 chamber back and forth between one end position in which said platform is adjacent one of said ports and a second end position in which said platform is adjacent the other of said ports, and means for heating the roof 25 of a portion of said chamber intermediate said ports to a relatively high temperature and for heating roof portions adjacent said ports to a somewhat lower temperature.
5. In a kiln the combination with a kiln chamber formed with two spaced-apart ware 30 inlet and egress ports and a carrier having a ware support platform movable in said chamber back and forth between one end position in which said platform is adjacent one of said ports and a second end position 35 in which said platform is adjacent the other of said ports, and kiln heating means comprising a combustion chamber in a portion of the wall of said chamber between said ports, and flues in portions of the wall of said chamber adjacent said ports through which the heating gases pass in opposite directions away from said combustion chamber.

Signed at Cleveland, in the county of 40
Cuyahoga and State of Ohio, this 10th day
of September, A. D. 1925.

PHILIP D'HUC DRESSLER.
